Primary Examiner — Melanie Pellegrini

(57)

CLAIM

The ornamental design for a buckle, as shown and described.

DESCRIPTION

1. Buckle
- 1.1 : Perspective
- 1.2 : Front
- 1.3 : Back
- 1.4 : Right
- 1.5 : Left
- 1.6 : Top
- 1.7 : Bottom

(Continued)

The buckle of the present design is shown in greyscale, as protection of the present design is not to be limited to a specific colour and/or combination of colours of the buckle and of its parts.

1 Claim, 7 Drawing Sheets
